UNITED STATES PATENT OFFICE

GEORGE H. RAU AND WILLIAM L. RAU, OF CLEVELAND, OHIO

AREA-WAY CONSTRUCTION

Application filed November 13, 1929. Serial No. 406,884.

This invention relates to area-way construction in connection with building operations where windows are provided below grade.

5 An object of the present invention is to provide an improved type of area-way structure which may be economically manufactured in the form of standardized sectional units, adapted to be readily placed in position with respect to the wall of a building and a window provided in such wall below grade.

The walls of area-way structures are ordinarily made of the same materials and at the same time as the building walls with 15 which they are associated. It has thus been necessary to build, in the area-way excavation, two side walls and an outer wall, and to install in the area-way proper an area-way basin, and a grating or grille for covering 20 the top of the area-way.

By the present invention, the work of making such area-way structures is greatly simplified, and the cost thereof is considerably reduced. This invention contemplates the 25 casting from reinforced concrete, or other suitable material, a floor or basin section, a plurality of area-way wall sections, and a top coping section having grating bars embedded therein, which sections are superimposed 30 and joined in the area-way excavation to form a complete area-way structure abutted against the building wall at the sides of and below the window opening in the latter. The building wall is furnished with brick corbels 35 to sustain the inner portion of the basin section at opposite sides of the window, and the numeral of wall sections may be varied according to the depth of the area-way excavation. Moreover, the structure may be 40 readily installed after completion of the building wall and without alteration of the latter.

The invention will be clearly understood 45 from the following description when considered in connection with the accompanying drawings; in which

Figure 1 is a central vertical section through a building wall and an area-way construction embodying the present invention.

Figure 2 is a horizontal section on line 2—2 of Figure 1.

Figure 3 is an enlarged fragmentary vertical section on line 3—3 of Figure 1.

Figure 4 is a view similar to Figure 2, 55 showing application of the invention to a building wall having a pair of adjacent windows below grade; and

Figure 5 is a view similar to Figure 2 showing how the form of the wall and coping 60 sections may be varied to suit conditions where wide windows are provided and a narrow area-way is desired.

Referring in detail to the drawings, 5 indicates a vertical wall portion which may be 65 of curved, rectangular or other desired contour. This vertical wall is erected on a floor section 6, forming the area-way basin, the upper surface of which may slope downward to a centrally disposed drain opening 7. The 70 floor section 6 has an integral horizontal extension 8 centrally of its outer edge adapted to project outwardly of the vertical wall portion 5 so as to provide additional support and so that when the earth is filled in the excavation outside said wall portion, part of the earth will bear on the extension 8 and anchor the floor section in place.

The wall portion 5 is constructed of a plurality of horizontal superimposed sections 9, 80 and disposed on the uppermost wall section 9 is a top or coping section 10. The inner vertical edges of the sections 9 and 10 are preferably beveled outwardly as at —b— so as to insure smooth joints on the inside of the 85 structure where these edges contact the building wall 11, even though there be a slight irregularity in the outer surface of said wall. Any spaces left at these joints may be filled with mortar, or the like.

The inner edge of the floor section 6 abuts the outer face of the building wall 11 below the window opening 12 of the latter, the inner portion of said floor section being sustained by brick or other corbels 13 provided on the 95 several sections of the structure are joined by means of metallic dowel pins 14 and without the use of mortar or cement, while the sections 6 and 10 are preferably reinforced by suitable means, such as rods 15, and the 100

wall sections 9 by suitable means, such as wire mesh fabric 16.

Grating bars 17 have their ends embedded or set in recesses in the opposite sides of the top or coping section 10.

5 The pre-cast sections of the area-way structure thus described may be manufactured in quantities at low cost, and the installation thereof may be readily and cheaply effected.

In such installation, a drain pipe 18 is laid 10 somewhat below the inner portion of the floor section 6, and the excavation below this portion is filled with cinders or gravel as at 19 to facilitate passage of water from the drain opening 7 to this drain pipe 18. A shallow

15 layer or bed of sand may be provided beneath the outer portion of the floor section 6 and its extension 8 for a similar purpose and to facilitate levelling of said floor section and provide a uniform bearing surface.

20 Where a pair of adjacent narrow windows are provided below grade, smaller area-way structures may be installed side by side as shown in Figure 4, while structures of laterally narrow form may be provided when desired for wider windows as shown in Figure 5.

25 Minor changes are contemplated within the spirit and scope of the invention as claimed.

What we claim as new is:

30 1. In combination, a foundation wall having a window opening therein leading to an area-way excavation and provided with exterior corbels directly below and at opposite sides of said window opening, and an area-way structure set in said excavation opposite said window opening, said area-way structure comprising a pre-cast bottom basin section having a drain opening and set upon the bottom of said excavation with its inner portion seated upon and sustained by said corbels, a plurality of superimposed pre-cast vertical wall sections set upon the bottom basin section, and a pre-cast top coping section set upon the uppermost vertical wall section, the inner edge of the bottom basin section 35 flatly abutting said foundation wall directly below the window opening, and the ends of said vertical wall sections and the top coping section abutting said foundation wall at opposite sides of the window opening.

40 16 2. A construction as specified in claim 1, wherein the bottom basin section has a horizontal projecting extension centrally of its outer edge upon which earth is adapted to be filled for anchoring said bottom basin section against movement.

45 3. A construction as specified in claim 1, wherein dowel pins form the sole means for joining all of the said sections and for maintaining them against relative lateral shifting.

46 4. A construction as specified in claim 1, in combination with a covering for the area-way structure embodying grating bars extending across the top coping section and

having their ends embedded in opposite sides of the latter.

5. A construction as specified in claim 1, wherein the vertical end edges of the vertical wall sections are bevelled outwardly.

70 In testimony whereof we affix our signatures.

GEORGE H. RAU.
WILLIAM L. RAU.
